Project CIP(57) **CLAIM**

The ornamental design for a gua sha device as shown and described.

DESCRIPTION

FIG. 1 is a top perspective view of the gua sha device, showing my new design;

FIG. 2 is a bottom view thereof;

FIG. 3 is a first side view thereof;

FIG. 4 is a second side view thereof;

FIG. 5 is a third side view thereof;

FIG. 6 is a fourth side view thereof;

FIG. 7 is a top view thereof; and,

FIG. 8 is a bottom view thereof.

The broken lines shown are for the purpose of illustrating portions of the gua sha device which form no part of the claimed design.
